UNITED STATES PATENT OFFICE.

GARRETT C. DEE, OF HARTFORD CITY, INDIANA.

BOILER-TUBE EXTRACTOR.

1,273,831.

Specification of Letters Patent. Patented July 30, 1918.

Application filed April 19, 1916. Serial No. 92,206.

To all whom it may concern:

Be it known that I, GARRETT C. DEE, a citizen of the United States, residing at Hartford City, in the county of Blackford 5 and State of Indiana, have invented certain new and useful Improvements in Boiler-Tube Extractors; and I do hereby declare the following to be a full, clear, and exact description of the invention, such as will 10 enable others skilled in the art to which it appertains to make and use the same.

This invention relates to a tool which is particularly designed for uncrimping or straightening the ends of boiler tubes, for 15 facilitating their removal from a boiler, and the primary object of the invention is to provide a tool as specified, which is extremely simple in construction, and efficient in operation.

20 A further object of this invention is to provide a tool as specified, which includes a handle bar having a head formed upon one end of the same, which head is shaped for engaging the interior of a boiler flue, and 25 rounded so as to permit of a pivotal movement of the tool without marring or rupturing the interior of the flue, and a crimp engaging and straightening member which is pivotally connected to the handle and is 30 moved into firm engagement with the interior of the crimp of the boiler flue by means of a wedge which is driven into an opening formed in the handle bar and engages the rear edge of the crimp engaging 35 member.

With the foregoing and other objects in view, this invention consists in such novel features of construction, combination and arrangement of parts as will be hereinafter 40 more fully described, illustrated in the accompanying drawings and claimed.

In describing the invention in detail reference will be had to the accompanying drawings wherein like characters designate 45 like and corresponding parts throughout the several views, and in which:—

Figure 1 is a perspective view of the improved boiler tube extractor.

Fig. 2 is a sectional view through the head 50 of the same having the wedge removed therefrom, and

Fig. 3 is a view similar to Fig. 2 showing the wedge inserted in the opening formed in the handle bar.

Fig. 4 is a view showing the application 55 of the boiler tube extractor.

Referring more particularly to the drawing, 1 designates the handle or body bar of the tool as an entirety, which has one portion rounded as shown at 2, for forming a hand 60 grip. The body bar 1 has a head 3 formed upon its end opposite to the rounded portion, which head is shaped for insertion into the interior of a boiler flue, and is provided with a cut out portion indicated at 4 for preventing binding action between the head and the rounded portion of the flue. The head 3 is curved, so as to permit of a pivotal or downward movement of the tool without marring or mutilating the interior of the 70 flue, and also to act as a fulcrum for the pivotal movement of the tool.

The body bar 1 is provided with an opening 5 extending transversely therethrough, through which the shank 6 of the crimp or 75 bead engaging jaw 7 extends. The head 8 of the bead or crimp engaging jaw is curved, and is provided with an inserting edge 9 which is adapted for insertion between the crimped or beaded end of a flue and a boiler 80 plate.

When the tool is initially applied for uncrimping the end of a boiler flue for facilitating its extraction from the boiler, the head 3 is positioned interiorly of the flue, 85 and the inserting edge 9 is positioned at the upper edge of the crimp or bead and against the boiler plate. The wedge 10 is then driven into the opening 5 back of the shank 6, which will move the upper end or head 8 90 of the jaw 7 forwardly and downwardly upon its pivotal pin 11, for forcing it between the bead and the boiler plate. The handle 2 is then gripped and the entire tool is moved downwardly which will uncrimp or 95 straighten the beaded or crimped end of the flue for facilitating its removal from a boiler.

In reducing the invention to practice, certain minor features of construction, combination and arrangement of parts may necessitate alterations to which the patentee is entitled provided such alterations are comprehended within the scope of what is claimed.

What is claimed is:—

1. In a boiler-tube extracting tool, a body bar, one end of said body bar shaped to form a hand grip, a head formed upon the other

105

- end of said body bar, said head being curved for snugly fitting the interior of a boiler tube and acting as a fulcrum for pivotal movement of the tool, said body bar being 5 provided with concave portions immediately in the rear of said head, said body bar provided with an opening extending therethrough, a boiler tube engaging jaw having a shank, said shank extending through said 10 opening and being pivotally connected to said body bar, said jaw provided with an inserting edge, and a wedge for driving into said opening against the rear edge of said jaw for forcing said inserting edge between 15 a boiler tube bead and a boiler plate.
2. In a boiler tube extracting tool, a body bar having one end rounded to form a handle and the other end shaped for fitting against the interior of a boiler tube to act as a ful- 20 crum for the tool, said body provided with a vertical opening, a jaw having a shank, said shank extending through said opening and pivotally connected to said body, and a wedge for insertion into said opening against 25 the rear edge of said jaw for driving the jaw between a boiler head and a tube bead, the forward wall of said recesses limiting the pivotal movement of said jaw by said wedge.
3. In a boiler tube extractor, a body bar having the fulcrum head formed upon one end and provided with the vertical opening,

a jaw including a shank, said shank extending through said opening and pivotally connected to said body bar, a head formed upon 35 the upper end of said shank and including a downwardly extending portion having its lower end sharpened transversely to the length of the body for insertion between the bead of the boiler tube and a boiler head. 40

4. In a boiler tube extractor, a body bar having a fulcrum head formed upon one end and provided with a vertical opening, a jaw including a shank, said shank extending through said opening and pivotally connected to said body bar, a head formed upon 45 the upper end of said shank and including a downwardly extending portion having its lower end sharpened transversely to the length of the body for insertion between the bead of a boiler tube and a boiler head and means for engagement with said shank for pivotally moving said jaw to drive said sharpened edge between a tube bead and boiler head, the forward wall of said opening limiting the pivotal movement of said jaw. 50

In testimony whereof I affix by signature in presence of two witnesses.

GARRETT C. DEE.
